UNITED STATES PATENT OFFICE.

AUGUST RAHNN, OF ELIZABETH, NEW JERSEY.

TOOL-STOCK.

1,259,777.

Specification of Letters Patent. Patented Mar. 19, 1918.

Application filed October 11, 1917. Serial No. 195,972.

To all whom it may concern:

Be it known that I, AUGUST RAHNN, a citizen of the United States, residing at Elizabeth, in the county of Union and State 5 of New Jersey, have invented certain new and useful Improvements in Tool-Stocks; and I do declare the following to be a full, clear, and exact description of the invention, such as will enable others skilled in the art 10 to which it appertains to make and use the same.

My invention has for its object to provide a comparatively simple and inexpensive, yet a highly efficient and durable tool for either 15 driving or removing screws in corners and other places which are practically inaccessible to the ordinary screw driver.

With the foregoing general object in view, the invention resides in the novel features of 20 construction to be hereinafter fully described and claimed, the descriptive matter being supplemented by the accompanying drawing which forms a part of this specification and in which:—

25 Figure 1 is a side elevation of the improved screw driver; and

Fig. 2 is a sectional view on the plane indicated by the line 2—2 of Fig. 1.

In the drawing above briefly described, 30 the numeral 1 designates a straight one piece tool shank whose front end is shown equipped with an integral screw driver blade 2, whereas the rear end of said shank is provided with a fork 3 forming part of a universal joint. The other fork 4 of the universal joint, is carried by the front end of a straight one piece handle shank 5, whose rear end is equipped with a hand grip 6 disposed in alinement with the body of the 35 shank as shown. A connecting member 7 is received in the two forks 3 and 4 and pivoted thereto by pins or the like 8 and 9 which are disposed at right angles to each other. By this arrangement, it will be obvious that the handle shank 5 may be swung 40 to any convenient angular relation in respect to the tool shank 1, yet that turning of the handle shank will operate the tool shank, regardless of the angle between the two, due 45 to the universal joint.

Near its front end, the tool shank 1 is provided with a fixed collar 10, and between this collar and the fork 3, a one piece U-shaped metal yoke 11 is positioned, the parallel arms of said yoke having openings 12

through which the tool shank 1 passes rotatably, said arms bearing against the collar and fork so that relative shifting is prevented. The cross bar 13 of the yoke 11 preferably converges forwardly with the 60 shank 1 as shown clearly in Fig. 1, said bar being provided with a rigid laterally extending hand grip 14 positioned at right angles thereto, said grip preferably having a lateral foot 16 secured by rivets or the like 65 17 to the cross bar 13, although it will be understood that any other suitable construction could well be employed.

In operation, the hand grip 14 is used to steady the tool and to force it against the 70 work, while rotation of the grip 6 will drive the tool as will be clear.

The device is extremely simple and inexpensive, yet will be highly efficient for driving and removing screws in otherwise accessible places, and since probably the best results are obtained from the specific features of construction shown and described, these features constitute the preferred form 75 of the tool. I wish it understood, however, 80 that within the scope of the invention as claimed, numerous minor changes may well be made.

I claim:

1. A tool of the class described comprising 85 a straight one piece tool shank, a straight one piece handle shank having a hand grip on its rear end and in line with said handle shank, a universal joint connecting the front end of said handle shank and the rear end 90 of said tool shank, a fixed collar near the front end of said tool shank, a one piece U-shaped yoke having openings in its arms through which said tool shank passes rotatably, said arms being positioned between 95 and bearing against said universal joint and said collar, and a rigid hand grip extending laterally from the cross bar of said yoke.

2. A structure as specified in claim 1, said cross bar of said yoke converging forwardly 100 with said tool shank, and said lateral hand grip extending at right angles from said cross bar.

In testimony whereof I have hereunto set my hand in the presence of two subscribing 105 witnesses.

AUGUST RAHNN.

Witnesses:
